Primary Examiner — Marianne Pandozzi*Assistant Examiner* — Jae Liang(74) *Attorney, Agent, or Firm* — Peacock Myers, P.C.; Janeen Vilven(57) **CLAIM**

The ornamental design for a keg dispensing housing, as shown and described.

DESCRIPTION

FIG. 1 is a perspective view of a keg dispenser housing showing my design in its open position;

FIG. 2 is a perspective view thereof with the upper keg doors closed;

FIG. 3 is a perspective view thereof with the lower door closed;

FIG. 4 is a front plan view thereof;

FIG. 5 is a back plan view thereof;

FIG. 6 is a right side plan view thereof;

FIG. 7 is a left side plan view thereof;

FIG. 8 is a top plan view thereof; and,

FIG. 9 is a bottom plan view thereof.

The broken lines are for illustrative purposes only and form no part of the claimed design.
